UNITED STATES PATENT OFFICE

2,674,818

DIGGING ATTACHMENT FOR BULLDOZERS

Earl Carnes, Safford, Ariz.

Application October 18, 1948, Serial No. 55,066

1 Claim. (Cl. 37—145)

1
The present invention relates generally to new and useful improvements in earth handling equipment and more particularly to a digging or scarifying attachment for the moldboard of a bulldozer.

An important object of the invention is to provide a plurality of digging or scarifying teeth pivotally attached at the upper edge of the moldboard of a bulldozer together with hydraulic means controlled by the operator of the bulldozer for raising and lowering the teeth into and out of digging position in front of the moldboard.

A further object of the invention is to provide a digging attachment of this character including a plurality of uprights detachably secured at their upper ends to a shaft rockably mounted at the upper edge of a moldboard, rigidly connecting the uprights to each other by cross bars and providing detachable teeth for the lower ends of the uprights whereby any one of the teeth, or uprights may be removed and replaced, should the same become damaged, without necessitating complete removal of the digging attachment.

A still further object is to provide an attachment of this character of simple and practical construction, which may be easily and quickly mounted in position on the moldboard of a bulldozer, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view;

Figure 2 is a front elevational view;

Figure 3 is a top plan view; and

Figure 4 is a group perspective view showing one of the detachable uprights and teeth for the digging attachment.

Referring now to the drawings in detail wherein for the purpose of illustration I have disclosed a preferred embodiment of the invention the numeral 5 designates generally a bulldozer of conventional construction and which includes a moldboard 6 supported at the front end of a vertically adjustable frame 7 to provide for the raising and lowering of the moldboard in the usual manner.

A shaft 8 is rockably mounted in bearing brackets 9 secured to the upper edge of the moldboard, the shaft having pairs of spaced apart

parallel lugs 10 welded or otherwise suitably secured thereto and extending downwardly therefrom. An upright 11 is secured at its upper end between each pair of lugs 10 by a bolt and nut 5 or the like 12 to detachably connect the upright in a rigid position to the shaft for raising and lowering movement of the upright by a rotation of the shaft.

The uprights 11 are rigidly connected to each other for uniform raising and lowering movement by means of upper and lower crossbars 13 and 14 also provided with pairs of spaced parallel lugs 15 projecting rearwardly therefrom and detachably secured to the uprights.

15 Channel-shaped teeth 16 are detachably secured to the lower end of the uprights 11 to project downwardly below the lower edge of the moldboard 6 as shown in Figure 1 of the drawing.

20 Arms 17 are suitably secured at one end to the shaft 8 and extend upwardly and forwardly therefrom and to the upper ends of which piston rods 18 are pivotally attached and extend downwardly in hydraulic cylinders 19 which are pivotally attached at their lower ends to the front portion of the frame 5. Fluid pressure supply lines 20 are suitably attached to the cylinders 19 for operating pistons (not shown) working in the cylinders in the usual manner to move the piston rods 18 inwardly and outwardly to raise and lower the digging attachment. Pressure is supplied to the cylinders 19 by the usual hydraulic lift of the bulldozer.

25 Angular brackets 21 are attached to each end of the cross bars 13 and 14 for engaging the side edges of the moldboard 6 when the digging attachment is lowered in front of the moldboard to hold the cross bars from endwise movement and thus rigidly hold the uprights 11 against lateral twisting or shifting movement on the moldboard.

30 Any one of the uprights 11 or teeth 16 may be easily and quickly removed and replaced when desired, without disturbing the other parts of the attachment.

35 In view of the foregoing description taken in conjunction with the accompanying drawings it is believed that a clear understanding of the device will be quite apparent to those skilled in this art. A more detailed description is accordingly deemed unnecessary.

40 It is to be understood, however, that even though there is herein shown and described a preferred embodiment of the invention the same 55 is susceptible to certain changes fully compreh-

hended by the spirit of the invention as herein described and the scope of the appended claim.

Having described the invention, what is claimed as new is:

In combination, an earth working implement including a vertically swingable frame having a moldboard at its front end, bearing brackets at the upper edge of the moldboard, a shaft journaled in the bearing brackets, pairs of spaced apart apertured lugs projecting downwardly from the shaft, a plurality of uprights rigidly secured at their upper ends between said pairs of lugs and supported downwardly in front of the moldboard for vertical swinging movement by the turning of the shaft, teeth at the lower ends of 15 the uprights, a cross bar having pairs of spaced apart lugs arranged in straddling position with respect to the uprights and attached thereto for rigidly connecting the uprights to each other, a crank arm fixed to the shaft, and a hydraulic 20

cylinder carried by the frame and connected to the crank arm for rocking the shaft to raise and lower the uprights.
